UNITED STATES PATENT OFFICE.

WILLIAM V. ROBINSON, OF OWOSSO, MICHIGAN, ASSIGNOR TO THE INDEPENDENT STOVE CO., OF OWOSSO, MICHIGAN, A CORPORATION OF MICHIGAN.

GAS BURNER.

Application filed November 30, 1921. Serial No. 518,752.

To all whom it may concern:

Be it known that I, WILLIAM V. ROBINSON, a citizen of the United States of America, residing at Owosso, in the county of Shiawassee and State of Michigan, have invented certain new and useful Improvements in Gas Burners, of which the following is a specification, reference being had therein to the accompanying drawings.

10 The invention relates to gas burners for cooking stoves and ranges and is more particularly designed for use in ovens which are arranged on a shelf above an open top cooking range. It is usual in the placing 15 of gas burners in ovens to provide perforations or apertures in the oven bottom adjacent to the gas burner for supplying the air required for the supporting of combustion. Where, however, the oven is arranged above an open top cooking range, the steam rising from utensils on the open top will enter these apertures in the oven bottom and cause the rapid deterioration 20 of the parts through corrosion. The omission of the apertures in the bottom will ordinarily greatly interfere with the proper 25 operation of the burner and, in fact, will usually put out the flame, inasmuch as the amount of air supply in the mixer is insufficient to completely support combustion.

It is the object of the present invention to avoid the difficulties above referred to and also to improve the operation of the burner. This is accomplished by placing 30 an imperforate bottom below the burner and also ranging in connection therewith a hood which separates the atmosphere above the burner from that at the side thereof, but which is cut away for the passage therethrough of the burner tips. This hood also provides clearance at each side of each burner tip sufficient for the passage of air for supporting combustion, such air being supplied to the hood from a lateral conduit. This conduit extends to the rear of 40 the shelf, which supports the oven and receives the air which is free from steam.

In the drawings:

Figure 1 is a horizontal section through 50 a portion of an oven showing my burner and hood in plan view;

Figure 2 is a vertical section thereof;

Figure 3 is a cross-section through one 55 of the burner tips with the hood adjacent thereto.

A is the back of a gas range rising above the open top (not shown), and B is a forwardly projecting shelf upon which is supported an oven C. The shelf B is imperforate so as to prevent any steam rising 60 from the open top gaining access to the oven. Also, the back A will prevent the steam from passing in rear of the oven. D is the gas burner of any suitable construction, having a mixing tube E which passes 65 laterally to one side of the stove. As shown, the burner D has an annular series of jet apertures F and radial series of jet apertures F' extending outward therefrom. G is a hood which is arranged above the 70 oven bottom or shelf B and which is connected with a lateral extension H leading rearwardly and connecting with an aperture I in the back A. The hood G completely surrounds the burner and provides 75 a chamber of sufficient capacity to supply air to all portions of the burner. The top of the hood is slightly below the top of the burner and is cut away to extend parallel to the radial arms thereof, leaving a narrow 80 slit J for the upward passage of air.

In operation, when the burner is lighted, the upward draft generated by the flame from the burner tips will cause the passage 85 of air through the slits J to form an envelope surrounding the flame and supporting combustion thereof. This envelope of pure air will exclude the air mixed with products of combustion which is present in the oven and which otherwise would be drawn towards the flame, interfering with combustion.

While I have described my improved burner as applied to ovens above open top ranges, it is obvious that it will work equally 90 well in other locations and that the narrow slit adjacent to the burner tip will direct air against the heated metal so as to raise the temperature and better support combustion.

What I claim as my invention is:

1. The combination with a gas burner, of a device for admitting air thereto comprising a hood surrounding said burner cut away for the passage of the burner tips therethrough and providing clearance for the passage of a thin stream of air slightly below and adjacent the edge of said burner tips.

2. The combination with a gas burner, of

a device for admitting air thereto comprising a hood surrounding the same cut away for the passage of the burner tips and providing parallel walls slightly below the edge 5 of said tips for directing a narrow stream of air adjacent to the flame and in contact with the heated wall of the burner.

3. The combination with a gas burner, and an imperforate wall arranged beneath 10 the same, of an air supplying device for said burner comprising a hood surrounding said burner cut away for the upward passage of the burner tips and providing a clearance for the upward passage of a narrow stream 15 of air adjacent to the flame, an integral laterally extending conduit for supplying air to the hood and means for securing said hood and conduit to said imperforate wall.

4. The combination with a gas range having an elevated imperforate shelf and an oven supported thereon, of a gas burner for said oven above said shelf and an air supplying device therefor comprising a hood surrounding said gas burner and cut away for the 25 passage of the burner tips with a clearance for the upward passage of a narrow stream of air for supporting combustion of the flame, and an integral conduit for supplying air to said hood extending to the rear of 30 said shelf.

5. In a gas range, the combination with a vertically extending back and an elevated imperforate shelf projecting forward therefrom, with an oven supported on said shelf, of a gas burner above said shelf and an air 35 supplying device therefor comprising a hood cooperating with said imperforate shelf in surrounding said gas burner and cut away for the passage of the burner tips and providing a clearance for a narrow 40 stream of air adjacent to the flame, and an integral conduit for supplying air to said hood extending rearward and receiving air from in rear of said back.

6. The combination with an imperforate 45 wall of a gas burner mounted thereabove, and an air supplying device for said burner comprising a sheet metal hood adapted to fit over said burner and cut away to permit of the protruding therethrough of the 50 burner tips and said cut away portion forming a passage-way for a narrow stream of air adjacent to the flame, an integral laterally extending conduit for supplying air to said hood and flanges on said hood and conduit respectively adapted to be secured to said imperforate wall.

In testimony whereof I affix my signature.

WILLIAM V. ROBINSON.
